UNITED STATES PATENT OFFICE

168,264

TIE HANGER

George J. Homola, Berwyn, Ill.

Application July 11, 1952, Serial No. 20,561

Term of patent 7 years

(Cl. D33—8)

To all whom it may concern:

Be it known that I, George J. Homola, a citizen of the United States, residing at Berwyn, in the county of Cook and State of Illinois, have invented a new, original, and ornamental Design for a Tie Hanger, of which the following is a specification, reference being had to the accompanying drawing, forming part thereof.

Figure 1 is a perspective view of a tie hanger, showing my new design;

Figure 2 is a side elevational view thereof; and Figure 3 is a top plan view of the same.

I claim:

The ornamental design for a tie hanger, as shown.

GEORGE J. HOMOLA.
